UNITED STATES PATENT OFFICE.

LARS M. LANDING, OF GLENWOOD, MINNESOTA.

INTEREST-COMPUTING MACHINE.

SPECIFICATION forming part of Letters Patent No. 665,118, dated January 1, 1901.

Application filed May 25, 1900. Serial No. 17,963. (No model.)

To all whom it may concern:

Be it known that I, LARS M. LANDING, a citizen of the United States, and a resident of Glenwood, in the county of Pope and State 5 of Minnesota, have invented new and useful Improvements in Interest-Computing Machines, of which the following is a full, clear, and exact description.

My invention relates to machines for computing interest and time, and has for its object to provide a machine of this class which will enable an operator to readily figure the interest on various principals at various rates and for various times and which will also enable the operator to readily ascertain the time 15 (number of days) between two given dates.

The invention will be fully described hereinafter and the features of novelty pointed out in the appended claims.

Reference is to be had to the accompanying drawings, forming a part of this specification, in which similar characters of reference indicate corresponding parts in all the figures.

Figure 1 is a plan of my improved calculator with parts broken away. Fig. 2 is a cross-section substantially on the line 2 2 of Fig. 4. Fig. 3 is a detail plan of a locking device with parts in section, and Fig. 4 is a plan of part of the machine drawn upon an enlarged 30 scale.

The machine comprises a base or frame A of any suitable shape—for instance, octagonal, as shown—and said base carries a top plate A' in the shape of a ring surrounding a central circular opening. The top plate is held in proper position relatively to the base A by means of a spacing-strip A². At one side of the machine a stop or finger B is secured to the top plate A', the inner end of 35 said finger extending beyond the top plate. At the other side the top plate A' is provided with a radial slot A³, and along the edge of the slot are produced in a space A⁴ the words and indications "Days," "6%," "7%," "8%," 40 "10%," "Mo.," "Day," it being understood that the range of percentages may be varied. The top plate A' has also secured to it, adjacent to the slot A³, a supporting-plate A⁵, provided with a guide and stop A⁶, engaging 45 the periphery of a disk C, pivoted to said

supporting-plate at C'. Corresponding to the columns in the space A⁴ lines A⁷ extend from the slot A³ to the periphery of the disk C, and these lines are adapted to register with the ends of radial lines C² upon said 55 disk. The disk is divided into a plurality of sections C³, the width of each section at the periphery being equal to the distance between the outermost lines A⁷. Adjacent to the periphery the disk has spaces C⁴, in which are 60 produced numbers indicating the interest on ten dollars for the number of years indicated at a at the rates indicated in the space A⁴. Thus if the disk C is turned until the section C³ so lettered in the drawings registers 65 with the lines A⁷ it will be seen at a glance that the interest on ten dollars for one year is "\$0.6," "0.7," "0.8," and "1.0," respectively, at the rates of six, seven, eight, and ten per cent., while the interest for five years 70 is indicated as "\$3.0," "3.5," "4 0," and "5.0." The disk C, with the arrangement shown in the drawings, indicates the interest for any number of years from one to eight. The disk may be turned by means of a pointed 75 tool, such as a pencil, inserted into recesses or apertures C⁵.

To the base A is secured a stationary central pivot D, which extends through a sleeve E, mounted thereon loosely and provided with 80 a plate E', which is secured to a disk F, extending outwardly under the top plate A' to within a short distance of the spacing-strip A². On top of this disk F is loosely mounted a smaller disk G, the periphery of which is 85 adjacent to the inner edge of the top plate A'. On the sleeve E are further loosely mounted a pointer H, having produced upon it the numerals "1" to "9" in their regular sequence, a washer I, two opposing cam-handles J, another washer I', and a nut K. The handles J are made, as shown in Fig. 2, with annular ribs J', which are wedge-shaped and adapted to engage each other, the obvious effect of turning the handles in one direction 90 consisting in forcing the washer I, pointer H, and disk G down against the disk F, so that both disks will be held to rotate in unison. When, however, the handles are turned in the opposite direction, the pressure will be 95 100

relieved and the upper disk G will be capable of rotating independently of the lower disk F. The annular ribs J' of the handles J inclose a space J², within which is located a spring L, the ends of which take into recesses in the respective handles, the spring assisting in holding the handles in the position shown in Fig. 3. This spring may, however, be omitted.

10 The lower disk is provided at its periphery with a notch F', adapted to be engaged by a latch M, pivoted at M' to the base A to hold the disk F in its normal or initial position. The disk F is provided with a series of numeral-columns corresponding and adapted to register with the columns in the space A⁴ of the top plate A'. Thus the outermost ring or column N contains the numbers of days from "1" to "360," this being the number of 15 days in an interest-year. The next rings or columns N' contain the corresponding amounts of interest at the rates in the space A⁴, and the columns N² contain the number of days expressed in months of thirty days 20 and days. Thus when, as in Fig. 1, the disk F is turned to bring the number "116" of the column N into view in the slot A³ there will appear in the columns N² the equivalent of one hundred and sixteen days—three 25 months and twenty-six days—and in the columns N' the interest on ten dollars for one hundred and sixteen days at six, seven, eight, and ten per cent. as "\$0.1933," "0.2256," "0.2577," and "0.3222," respectively. The 30 mills and tenths of mills are given in order that the interest on one hundred dollars and one thousand dollars may be found accurately by simply shifting the period one or two spaces to the right. The upper disk G likewise has a series of concentric rings of figures, divided into twelve sectors, bearing the names of the months in the space O. In the outer ring O' are disposed the numerals "1" to "30" for each month, (the thirtieth space 35 being left a blank for the month of February,) and in this ring are also provided recesses or apertures P, one for each space, said recesses being adapted to receive a pencil or other pointed tool. At the beginning of the 40 month of January is located a radial line Q, termed and designed as the "New-Year" line. Preferably the sign + is produced adjacent to every month having thirty-one days and the sign - adjacent to February. The two 45 rings of figures O² next to the ring O on the inside contain successive numerals—for instance, those from "1" to "180"—and the innermost rings O³ are divided into just as many spaces as the rings O² and contain the 50 multiples (from "1" to "9") of the numbers contained in the inner ring O². The latter and the eight rings O³ are so arranged as to register with the numerals "1" to "9" on the pointer H. (See Fig. 4.) The top plate 55 A' is provided adjacent to the edge of the disk G with a series of numerals A⁸, running

from "1" to "360," the starting-point being at the stop B.

The manner of using the appliance for finding the interest on ten dollars, one hundred dollars, &c., for any period from one day up to eight years will be obvious. The disk C will give the amount of interest for entire years and the disk F for fractions of a year expressed in days or in months and days. To 60 find the interest on principals which are not multiples of ten, the pointer H and the rings O²O³ of the disk G are used. Suppose it is desired to find the interest on two hundred and fifty-seven dollars at six per cent. for a period 65 of one year and two hundred and seventy days. A pencil is then inserted into the aperture C⁵ of the disk C which is adjacent to the inner number "1" and the disk is turned until the pencil abuts against the stop A⁶. The disk will then indicate that the interest 70 on ten dollars for one year is "\$0.6" at six per cent. The handles J being then brought into the diverging position, (shown in Figs. 1 and 3,) so as to lock disks F and G together, the 75 lower disk F is turned by means of the handles J' until the number "270" on the outer ring N shows in the slot A³ of the top plate A'. The disk F will then show that the interest 80 on ten dollars at six per cent. for two hundred and seventy days amounts to "\$0.45." By addition it is therefore found that the interest on ten dollars at six per cent. for one year and two hundred and seventy days amounts to "\$1.05." Now the pointer H is 85 turned to register with the number "105" on the inner ring O² of the disk G. The number "2" of the pointer will then register with "210" in the outermost ring O³, the number "5" of the pointer will register with "525," 90 and the number "7" with "735." These three numbers, "210," "525," and "735," 95 will then be added in the customary way, (partial products of a multiplication,) thus

$$\begin{array}{r}
 210 \\
 525 \\
 735 \\
 \hline
 26985
 \end{array}$$

giving "\$26.985" as the interest on two hundred and fifty-seven dollars at six per cent. for one year and nine months, (two hundred and seventy days.) The same result can also be obtained in the following way: The interest on ten dollars at six per cent. for one year and nine months having been found to be one dollar and five cents, as before, the interest on two hundred dollars under the same conditions is written down as "\$10.5 + 10.5" and there remains to be found the interest on fifty-seven dollars. For this purpose the pointer H is turned to register with the number "57" on the inner ring O² of the disk G. The figure "1" of the pointer will 110 then give the number "57" and the figure "5" of the pointer will give the number 115

"285." These partial products being properly alined and added will yield the result:

$$\begin{array}{r}
 10.5 \\
 10.5 \\
 5.7 \\
 \hline
 5.285 \\
 \hline
 \$26.985
 \end{array}$$

10 This method of obtaining the result is preferable on account of being applicable in all cases, inasmuch as one of the factors will always be smaller than one hundred.

The machine is also used for ascertaining 15 the number of days between two dates. For this purpose and to ascertain the interest at the same time the lower disk F is first brought to the zero position. Then the handles J are turned so as to release the upper disk G, a 20 pencil inserted at the earlier date—say January 3—and the disk G turned around (in the same direction as the hands of a watch) until the pencil strikes the stop B. Preferably the latch M is thrown in during this 25 operation, so as to prevent an accidental turning of the disk F. Then the handles J are turned in the opposite direction, so as to connect the disks F and G for simultaneous movement, and the latch M is thrown out to 30 release the disk F. The pencil is then inserted into the recess P corresponding to the later date—say July 17—which will bring to the slot A⁸ of the top plate A' the number of 35 days, "194," (six months fourteen days,) and the interest figures "3233," "3772," "4311," and "5389." The numbers in the ring A⁸ are used when the number of days between two dates and one of said dates are given and it is desired to find the other date. This is 40 done by simply bringing the given date in registry with the pointer B or with the given number of days in the ring A⁸, according as the earlier or the later date is given.

In order to find the exact number of days 45 between two dates, there will have to be added one day for every month of thirty-one days, the last day of which is between said dates, and one or two days will have to be deducted if the last day of February is within the calculation.

The improved computing-machine may also be used for solving, at least approximately, various other problems, such as finding the time during which the interest on a given 55 principal will become equal to a given amount at a given rate.

Having thus described my invention, I claim as new and desire to secure by Letters Patent—

60 1. An interest-computing machine, comprising a frame having a central opening and a sight-opening or slot adjacent thereto, indications of interest rates adjacent to said sight-opening, a disk mounted to revolve in the frame and having a series of interest figures for different numbers of days, adapted to show through said sight-opening, another

disk pivoted about the same axis and bearing around its periphery indications of days and months, and mechanism for connecting 70 said disks to move in unison, or allowing the second-named disk to turn independently.

2. An interest-computing machine, comprising a frame having a sight opening or slot with indications of interest rates adjacent to 75 said opening, a disk mounted to revolve in the frame and having a series of interest figures for different numbers of days, adapted to show through said sight-opening, and another disk divided by radial lines into sectors and spaces giving the interest at various percentages for different numbers of years, said second disk being pivoted to the frame eccentrically in relation to the first-mentioned disk, and the frame being provided, 85 between the sight-opening and the periphery of the yearly-interest disk, with lines corresponding to the indications of interest rates adjacent to the sight-opening, said lines leading to the periphery of the yearly-interest 90 disk and being there separated by distances equal to the width of the spaces on said disk.

3. An interest-computing machine, comprising a frame having a central opening and a sight opening or slot adjacent thereto, indications of interest rates adjacent to said sight-opening, a disk mounted to revolve in the frame and having a series of interest figures for different numbers of days, adapted to show through said sight-opening, another 95 disk pivoted about the same axis and bearing around its periphery indications of days and months, two cam-handles mounted on the pivot of said disks and an abutment for the upper cam-handle, so that by turning the 100 handles in one direction the lower handle will be forced lengthwise of the pivot to press the upper disk into firm contact with the lower disk.

4. An interest-computing machine, comprising a frame having a central opening and a sight opening or slot adjacent thereto, indications of interest rates adjacent to said sight-opening, a disk mounted to revolve in the frame and having a series of interest figures for different numbers of days, adapted to show through said sight-opening, another 110 disk pivoted about the same axis and bearing around its periphery indications of days and months, said disk also bearing in concentric 115 rows or rings, a series of numerals in their natural sequence, together with the multiples of said numerals, and a pointer mounted to turn about the pivot of the disks, and provided with a consecutive series of numerals 120 arranged to register with the numbers and multiples on said second disk.

5. An interest-computing machine, comprising a base, a top plate having a central circular opening and a radial sight opening 125 or slot adjacent to the central opening, with indications of interest rates at said opening, and indications of day-numbers around the circular opening, a spacing-strip separating

the top plate from the base, a pivot secured to the base centrally, a sleeve loosely mounted on the pivot, a disk rigidly secured to said sleeve and projecting under the top plate, 5 said disk bearing a series of interest figures for different numbers of days, adapted to show through the sight-opening, another disk loosely mounted on said sleeve and fitting within the circular opening of the top plate, o said disk bearing around its periphery indications of days and months, and also bearing in concentric rows or rings, a series of numerals in their natural sequence, together with the multiples of said numerals, a pointer 15 mounted to turn on the sleeve and provided with a consecutive series of numerals arranged to register with the numerals and multiples on said second disk, a nut screwing on the sleeve, and two handles mounted to 20 turn on the sleeve between the said nut and the upper disk and provided with oblique surfaces or cams on their opposing sides, so that by turning the handles in one direction the lower cam-handle and the upper disk will 25 be forced lengthwise of the pivot to clamp the disks together.

6. An interest-computing machine, comprising a base, a top plate having a central circular opening and a radial sight opening 30 or slot adjacent to the central opening with indications of interest rates at said opening, and indications of day-numbers around the circular opening, a disk pivoted to the top plate exteriorly of its central opening and divided by radial lines into sectors and spaces giving the interest at various percentages for 35 different numbers of years, the top plate being provided with lines corresponding to the indications of interest rates adjacent to the

sight-opening and leading from said opening to the periphery of said disk, the distance between said lines, at the periphery of the disk, being equal to the peripheral width of the disk-spaces, a spacing-strip separating the top plate from the base, a pivot secured to 45 the base centrally, a sleeve loosely mounted on the pivot, a disk rigidly secured to said sleeve and projecting under the top plate, said disk bearing a series of interest figures for different numbers of days, adapted to 50 show through the sight-opening, a latch for locking said daily-interest disk, another disk loosely mounted on said sleeve and fitting within the circular opening of the top plate, said disk bearing around its periphery indications of days and months, and also bearing 55 in concentric rows or rings, a series of numerals in their natural sequence, together with the multiples of said numerals, a pointer mounted to turn on the sleeve and provided with a consecutive series of numerals arranged to register with the numerals and multiples on said second disk, a nut screwing on the sleeve, and two handles mounted to turn on the sleeve between the said nut 60 and the upper disk and provided with oblique surfaces or cams on their opposing sides, so that by turning the handles in one direction the lower cam-handles and the upper disk will be forced lengthwise of the pivot to 65 clamp the two disks together.

In testimony whereof I have signed my name to this specification in the presence of two subscribing witnesses.

LARS M. LANDING.
